UNITED STATES PATENT OFFICE.

WILLIAM ABRAM CONTANT, OF BRIGHTON, NEW YORK, ASSIGNOR TO F. B. PEASE CO.,
OF ROCHESTER, NEW YORK, A CORPORATION OF NEW YORK.

FOLDING STEP-LADDER.

1,246,395.

Specification of Letters Patent. Patented Nov. 13, 1917.

Application filed October 17, 1916. Serial No. 126,156.

To all whom it may concern:

Be it known that I, WILLIAM A. CONTANT, a citizen of the United States, residing at Brighton, Monroe county, State of New York, have invented certain new and useful Improvements in Folding Step-Ladders, of which the following is a specification.

This invention comprises improvements in step ladders and, more particularly, in short ladders having large tops, which may be used as stools.

The objects of the invention are to provide a step ladder of this type which is simple in construction, strong, durable and cheap to manufacture, and the parts of which are so connected that the device may be folded into small compass for storage.

The invention will be described in connection with the accompanying drawings, in 20 which,

Figure 1 is a side view of an unfolded step ladder embodying my invention;

Fig. 2 is a similar view of the same in its folded position;

Fig. 3 is an enlarged view of the upper portion of the ladder as seen looking toward the right in Fig. 2; and

Fig. 4 is a section along the line 4—4 of Fig. 3.

Referring to the drawings, the step ladder or stool comprises, as usual, a top or seat 10, a pair of front legs 11, which are the side rails of the steps when the device is used as a ladder, and a pair of rear legs 12. 35

Between the legs 11 may be arranged one or

more steps 13, of usual construction.

The legs are connected to the vertical flanges 14 of a pair of angular brackets, the horizontal flanges 15 of which are secured 40 to the under side of the top by screws or other suitable fastenings. The brackets extend from front to rear of the top, preferably across the grain of the wood and stiffen and support it.

The rear legs 12 are connected directly to the vertical downwardly extending flanges 14 by pivots 16. To the upper end of each front leg or rail 11 is securely fastened a hinge plate 17 which extends entirely across the 50 rail and has its upper edge flush with or slightly above the end of the rail. The hinge plates have rearwardly extending lugs 18, which are connected to the vertical flanges 14, respectively, by pivots 19. The forward 55 edges of the hinge plates 17 extend around

and protect the forward edges of the rails 11, as at 20. When the step ladder is set up for use, as shown in Fig. 1, the upper ends 21 of the protective portions 20 abut against the horizontal flanges 15 of the top brackets 60 and, at the same time, projections 22 of the hinge plates abut against the lower edges of the flanges 14, the ladder being preferably notched as at 23, to receive these projections. 65

The construction just described protects the front legs or rails 11 and the top, which parts are usually constructed of wood, and only metal parts abut and take the strains when the ladder is in use. When the ladder is folded the parts 20 of the hinge plates contact with the wall or other support against which the ladder may rest and protect the ladder from being marred. 70

The ladder folds very compactly, as 75 shown in Fig. 2, diagonal braces 24, which connect the front and rear legs, being so proportioned and pivoted as to permit of compact folding while forming rigid braces when the ladder is unfolded for use. 80

The brackets 14, 15 and the hinge plates 17 are preferably steel stampings which are at once light and strong. The brackets 14, 15 extend from front to rear of the top and support it throughout its width, preventing 85 splitting and warping, while the hinge plates extend across the side rails 11 of the steps and strengthen and protect them, in addition to forming abutments which receive the strain and weight of objects resting on the top. 90

A circular opening 24' in the top near the rear edge enables the top to be grasped with convenience when the ladder is to be folded or carried from place to place. 95

Having thus described the invention what is claimed and desired to be secured by Letters Patent is:

1. In a folding step ladder, a top, members secured to the under side of said top and extending across the same, two pairs of legs pivoted to said members, the ends of one pair of legs being adapted to abut against said members to limit the rotation of the legs about said pivots when the ladder is unfolded, and braces pivoted to and connecting the corresponding legs of each pair of legs. 100

2. In a folding step ladder, a top, angular brackets having horizontal portions secured 105

110

- to the top and vertical portions projecting downwardly therefrom, supporting legs arranged in pairs, the rear legs being directly pivoted to said brackets, hinge plates secured to the tops of the front legs, pivots connecting the hinge plates to the vertical portions of the brackets, the ends of the second pair of legs being adapted to abut against the horizontal portion of said brackets to limit the rotation of the legs about said pivots when the ladder is unfolded, and braces pivoted to and connecting the corresponding legs of each pair of legs.
3. In a folding step ladder, a top, angular brackets having horizontal portions secured to said top and having downwardly extending vertical portions, supporting legs arranged in pairs, one pair of said legs being directly pivoted to said brackets, the other pair of legs having hinge plates secured thereto at their upper ends, said hinge plates having upwardly extending lugs adapted to abut against the horizontal portions of the brackets when the ladder is unfolded to limit the rotation of the legs about the pivots, and braces pivoted to and connecting the corresponding legs of each pair of legs.
4. In a folding step ladder, a top, brackets secured to said top and having horizontal portions and downwardly projecting portions, supporting legs arranged in pairs, one pair of said legs being directly pivoted to said brackets, the other pair of legs having lateral projections at the upper ends which are pivoted to the downwardly projecting portions of the brackets, the ends of said second pair of legs being adapted to abut against the horizontal portion of said brackets to limit the rotation of the legs about said pivots when the ladder is un-

folded, and braces pivoted to and connecting the corresponding legs of each pair of legs.

5. In a folding step ladder, a top, brackets secured to the top and having horizontal portions and downwardly projecting portions, supporting legs arranged in pairs, one pair of said legs being directly pivoted to said brackets, the other pair of legs having hinge plates secured thereto with rearwardly extending portions pivoted to said brackets, the upper edges of the hinge plates being flush with the upper ends of the legs, the ends of said second pair of legs being adapted to abut against the horizontal portion of said brackets to limit the rotation of the legs about said pivots when the ladder is unfolded, and braces pivoted to and connecting the corresponding legs of each pair of legs.

6. In a folding step ladder, a top, angular brackets having horizontal portions secured to said top and having downwardly extending vertical portions, supporting legs arranged in pairs, one pair of said legs being directly pivoted to said brackets, the other pair of legs having hinge plates secured thereto at their upper ends, said hinge plates having rearwardly extending portions pivoted to said brackets, forward portions extending around the edge of the leg to protect the same, and upwardly extending lugs adapted to abut against the horizontal portions of the brackets when the ladder is unfolded to limit the rotation of the legs about the pivots, and braces pivoted to and connecting the corresponding legs of each pair of legs.

In testimony whereof I affix my signature. 80

WILLIAM ABRAM CONTANT.
